(57) **CLAIM**

We claim the ornamental design for a LED light fixture, as shown and described.

DESCRIPTION

FIG. 1 is a front perspective view of a LED light fixture of the invention;

FIG. 2 is a rear perspective view of the LED light fixture;

FIG. 3 is a front view of the LED light fixture;

FIG. 4 is a rear view of the LED light fixture;

FIG. 5 is a first side view of the LED light fixture; and,

FIG. 6 is a second side view of the LED light fixture.

The broken lines in FIGS. 1-6 are for the purpose of illustrating unclaimed features and form no part of the claimed design.
